CARRYING HANDLE FOR SEWING MACHINES

Wilbur J. Peets, Watchung, N. J., and Leonard C. Marsac, Freneuse, France, assignors to The Singer Manufacturing Company, Elizabeth, N. J., a corporation of New Jersey

Application May 19, 1951, Serial No. 227,126

7 Claims. (Cl. 112—218)

1

This invention relates to a sewing machine and more particularly to a sewing machine of the portable type.

The invention has as a primary object to provide a carrying handle for a portable sewing machine which may be folded flush with a surface of the machine.

Another object of the invention is to provide a portable sewing machine with a pivoted lifting handle which may be easily gripped when in its folded position for raising it to the carrying position.

A further object of the invention is to provide a pivotal connection between a carrying handle and a portable sewing machine which connection is sturdy and easy to assemble.

A still further object of the invention is to provide a detent mechanism for a pivoted lifting handle which will hold the handle in any one of a plurality of positions.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 is a rear elevational view of a portable sewing machine embodying the invention.

Fig. 2 is a top plan view of the sewing machine shown in Fig. 1.

Fig. 3 is a partial view taken on line 3—3 of Fig. 1.

Fig. 4 is a partial sectional view of the handle hinge structure taken on line 4—4 of Fig. 2.

Fig. 5 is a partial sectional view of the handle hinge structure taken on line 5—5 of Fig. 4.

Referring specifically to the drawings, a portable sewing machine is shown having the usual bed 11 carrying a curved bracket-arm 12 which terminates in a head 13. The bracket-arm indicated generally at 12 comprises a body portion 14 fastened to the bed 11 and a removable portion or cover-plate 15. A bed extension 16 is pivotally attached to the bed 11. The bracket-arm cover-plate 15 is attached to the body portion 14 by screws 17. The top of the cover-plate 15 is formed with parallel slots 18 and 19 extending from slots 20 and 21, respectively, in one edge of the cover-plate, substantially across its width. A U-shaped lifting handle 22 is provided with arms 23 and 24 positioned in the slots 18, 20 and 19, 21, respec-

2

tively, which arms are contoured to be flush with the upper surface of the cover-plate 15 when the handle is in retracted position, shown in solid lines in Fig. 4. The grip portion of the handle 22 is formed with a U-shaped cross-section as shown in Fig. 4. A depression 25 is formed in the top and edge of the cover-plate 15 between the slots 20 and 21 to receive the grip portion of the handle 15. Bearing bosses 26 and 27 depend from the lower surface of the cover-plate and are located one on each side of the slot 18 at its inner or blind end. One end of the arm 23 extends between the bosses 26 and 27 and is engaged by a pivot pin 28 passing through a hole 29 in the arm 16. The bosses 26 and 27 are provided with bearing slots 30 and 31, respectively, open at their lower ends to receive the pivot pin 28 after it is assembled in the handle arm. The end of the handle arm is formed as a cam having two flat faces 32 and 33 which are selectively engaged by a cantilever spring 34 fastened to the cover-plate 15 by a screw 35. As may be clearly seen in Fig. 4, the spring 34 presses against the end of the handle arm to hold the pivot pin 28 firmly seated in the bearing slots 30 and 31. Since the handle arm 24 is pivoted to the cover-plate in the same manner that the arm 23 is pivoted to said cover plate, a detailed description of the pivotal connection for the arm 24 is not believed to be necessary.

The handle is easily assembled to the cover-plate by positioning the arms of the handle in the slots 18 and 19 and inserting the pivot pins 28 through the journal holes 29 in the arms. The pivot pins 28 are seated in the slots 30 and 31 and the cantilever springs 34 are then fastened to the cover-plate to hold the handle and pivot pins in position. This cover-plate and handle assembly is securely attached to the body portion 14 by the screws 17.

When the sewing machine is not in use and is to be stored, the lifting handle 22 is pressed to the folded position shown in full lines in Figs. 1 and 4 of the drawings. In this position, the handle arms 23 and 24 are positioned in the slots 18, 20 and 19, 21, respectively, and the grip portion of the handle is positioned in the depression 25. Each cantilever spring 34 engages the flat face 32 of the cam on the end of a handle arm and retains the handle in the folded position, flush with the outer surface of the bracket-arm. Thus there is no protruding lifting handle which requires extra storage space. When it is desired to carry the machine, one's fingers may be easily engaged in the U-shaped grip portion of the

handle 22 to raise the handle to the position shown in broken lines in Figs. 1 and 4. In this position, each cantilever spring engages the flat face 33 of a cam and retains the handle in the upright position.

From the foregoing description, it is apparent that I have provided a simple lifting handle for a sewing machine which may be folded flush with the outer surface of the machine for convenient storage in a limited space. Further, the novel hinge construction for the handle provides a pivotal connection which is easily assembled and which also functions as a detent means for retaining the handle in selected positions.

Having thus described our invention, what we claim herein is:

1. A sewing machine having a bed, a bracket-arm carried by said bed and having a hollow horizontal portion terminating in a head, said bracket-arm having slots therein, a lifting handle positioned in said slots flush with the outer surface of said bracket-arm, said lifting handle having a pivot portion disposed in said slots, and a pivotal connection between said pivot portion of said handle and said bracket-arm.

2. A sewing machine having a bed, a bracket-arm carried by said bed, said bracket-arm comprising a hollow horizontal body portion and a removable cover-plate having a plurality of slots, a lifting handle positioned in at least one of the slots in said cover-plate flush with the upper surface of said cover-plate, said handle having pivot portions disposed in said slots, and pivotal connections between said handle pivot portions and the lower surface of said cover-plate.

3. A sewing machine having a bed, a bracket-arm carried by said bed and having a hollow horizontal portion terminating in a head, said bracket-arm comprising a body portion and a detachable cover-plate fastened to said body portion, said cover-plate being formed with parallel slots and a depression joining said slots, a lifting handle positioned in the slots and depression in said cover-plate, and pivotal connections between said handle and the lower surface of said cover-plate.

4. A sewing machine having a bed, a bracket-arm carried by said bed and having a hollow horizontal portion terminating in a head, a lifting handle, said bracket-arm having slots entered by said lifting handle, pivotal connections between said handle and the inner surface of said bracket-arm, cam means formed on said handle, and a spring carried by said bracket-arm and engaging said cam means.

5. A sewing machine having a bed, a bracket-arm carried by said bed and having a hollow horizontal portion terminating in a head, said bracket-arm comprising a body portion and a

removable cover-plate, a lifting handle having pivot arms, a cam formed on one end portion of each of said pivot arms, said cover-plate having slots entered by the pivot arms of said handle, pivot pins engaging said handle end portions, bearing bosses formed on the lower surface of said cover-plate and having open ended slots entered by said pivot pins, and springs carried by said cover-plate and engaging said cams adjacent the open ends of the slots in said bosses, whereby said pivot pins are retained in the bearing slots in said bosses.

6. A portable sewing machine having a bed provided with depending wall portions, a hollow bracket-arm having an upright portion carried by said bed and a horizontal portion terminating in a hollow head, said horizontal portion of said bracket-arm having side walls and a top cover-portion extending between said side walls, said top cover-portion having at least one handle-receiving slot formed therein, a retractable lifting handle disposed in said slot and having an operative and inoperative position, said handle being disposed a greater distance from one end of said bracket-arm than from the opposite end of said bracket-arm, and mechanism for operatively connecting said handle to said bracket-arm whereby said handle may be moved from said operative position to said inoperative position.

7. A portable sewing machine having a bed provided with depending wall portions, a hollow bracket-arm having an upright portion carried by said bed and a horizontal portion terminating in a hollow head, said horizontal portion of said bracket-arm having side walls and a top cover-portion extending between said side walls, said top cover-portion having at least one handle-receiving slot formed therein, a retractable lifting handle disposed in said slot and having an operative and inoperative position, said handle being disposed a greater distance from one end of said bracket-arm than from the opposite end of said bracket-arm, and mechanism for operatively connecting said handle to said bracket-arm whereby said handle may be moved from said operative position to said inoperative position, and resilient means for holding said lifting handle in each of said positions.
